(57) CLAIM

The ornamental design for a portable interior light with clip, as shown and described.

DESCRIPTION

FIG. 1 is an illustration of the invention in the environment of a purse shown in shadow outline, with the broken line showing for illustrative purposes only and forming no part of the claimed design;

FIG. 2 is a front elevation view of the portable interior light with clip of the invention;

FIG. 3 is a top plan view of the portable interior light with clip of the invention;

FIG. 4 is a rear elevation view of the portable interior light with clip of the invention;

FIG. 5 is a left side elevation view of the portable interior light with clip of the invention, it being understood that the right side elevation view is a mirror image thereof; and,

FIG. 6 is a bottom plan view of the portable interior light with clip of the invention.
